Attorney

UNITED STATES PATENT OFFICE.

GEORGE M. SHARP, OF WASHINGTON, DISTRICT OF COLUMBIA.

HEADDRESS.

1,394,366.

Specification of Letters Patent.

Patented Oct. 18, 1921.

Application filed April 22, 1920. Serial No. 375,863.

To all whom it may concern:

Be it known that I, GEORGE M. SHARP, a citizen of the United States, residing at Washington, in the District of Columbia, have invented certain new and useful Improvements in Headdresses; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 One of the objects of my invention is to provide a form of headdress of the turban type, which is adapted to be quickly adjusted about the head in the form of a turban and securely held in position by tying 20 the two ribbons carried thereby in a bow knot.

Another object of the invention is to provide a headdress of the character mentioned, which is adapted to fit the head of any 25 wearer.

Another object of the invention is to provide a headdress as described, which is designed to conform in every part thereof to the shape of the head, thereby, when adjusted in position, concealing the hair of the wearer, thus providing a device which is most admirably adapted for use by patients in dentists' chairs, or by nurses in hospitals, or the like, for sanitary reasons.

35 The accompanying drawings clearly disclose my invention, and the different figures of the drawings may be briefly described as follows:

Figure 1 is a perspective view of the device as placed upon the head of the wearer, 40 preliminary to adjusting the same about the head;

Fig. 2 is a similar view showing the first adjustment of the turban, after being placed 45 on the head;

Fig. 3 is a similar view, showing the second adjustment of the head gear;

Fig. 4 is a similar view, showing the adjusted position of the headdress;

50 Fig. 5 is a view similar to Fig. 4, but showing the back and side of the headdress;

Fig. 6 is a fragmentary view of the headdress, illustrating the curved cross-sectional, or bowed, form thereof, and

Fig. 7 is also a fragmentary view of the 55 headdress.

Referring now in detail to the drawings: The body portion of the headdress, or turban, is formed of two substantially rectangular pieces of suitable material, said pieces 60 being designated by the reference numerals 1, 1. Said pieces of the body portion are connected along their two adjacent ends by a seam 2, said seam extending from the point *a* to the point *b*, as clearly shown in Fig. 1. 65

At one end of the seam 2, said pieces 1, 1 are Shirred, as shown at 4, thus conforming said pieces 1, 1 to the curvature of the head of the wearer.

The lower ends of the depending portions 70 3, 3—that is to say, the free ends thereof opposite the seam 2—are gathered transversely, as shown at 5, 5, thereby emphasizing the curvature of said portions 3, 3, and conforming said portions 3, 3 to the curva- 75 ture of the head of the wearer.

The said gathered ends 5, 5 are gathered to the width of and attached to ribbon ties 6, 6.

In adjusting the headdress, or turban, to 80 the head of the wearer, the headdress is disposed on the head in the manner shown in Fig. 1; that is to say, with the seam 2 at the top of the head, and with the shirred portion 4 in the center of the forehead, at the top 85 thereof, the portions 3, 3 thus depending upon each side of the head of the wearer, as shown in Fig. 1. Thereupon, the portions 3, 3 are crossed in reverse directions at the base of the back of the head of the wearer, 90 as shown in Fig. 2; thereafter, said portions 3, 3 are drawn upward toward the front, along the sides of the head of the wearer, as shown in Fig. 3, completely concealing the hair of the wearer; and finally, the ribbons 95 6, 6 are tied in a bow 7, at the top of the forehead, centrally thereof, as shown in Fig. 4.

What I claim to be new is:

A head dress composed of two strips of 100 flexible non-elastic material, stitched together upon a line inclined to the marginal edges, said stitching including a gathering of the seam a distance from one end thereof and the remote end of said strips gathered to a tie.

In testimony whereof I hereunto affix my signature.

GEORGE M. SHARP.
